DUPLEX FLAT CONSTRUCTION

Francis J. Hinton, Wauwatosa, Wis.

Application December 21, 1950, Serial No. 202,044

6 Claims. (Cl. 20—1.1)

1

This invention relates to improvements in duplex flat constructions, and more particularly to a duplex flat construction having a unique stairway and door arrangement to provide complete separation of the first floor and second floor apartments while affording a separate front entrance for each of the two apartments and a common rear entrance which provides access to the building basement, the lower apartment kitchen and the stairway to the upper apartment.

Duplex flats are popular and economical forms of buildings for housing two families and include a lower floor apartment or flat and a second floor apartment or flat. In a duplex flat building it is desirable to provide complete privacy and separation as between the upper and lower apartments, and this is normally accomplished by a separate front entrance and stairway for the upper flat and a rear stairway to communicate with the kitchen portion of the upper flat with a common rear entrance for the latter, for access to the kitchen of the lower flat and to a basement stairway. Obviously, with the rise in building costs and the space consumed by the provision of separate front and rear stairways, the construction cost of a conventional duplex flat with separate front and rear stairways may be prohibitive. In less expensive conventional duplex flat constructions the front stairway for the upper apartment is eliminated and access to the upper apartment may only be had through the rear stairway which communicates with the kitchen and living room of the upper apartment and consequently requires that guests desiring to reach the living room of the upper flat must pass through the rear entrance or use a common front entrance.

With the foregoing in mind the primary object of the present invention is to provide a duplex flat construction which eliminates the need for separate front and rear stairways to the upper apartment but nevertheless provides separate front entrances for both the upper and lower apartments with a common rear entrance and stairway giving access to the kitchen of the lower apartment, the kitchen of the upper apartment and the basement of the building, while preserving privacy and separation as between all portions of the upper and lower apartments.

A more specific object of the invention is to provide a duplex flat construction having but a single stairway for the upper apartment, which stairway is so arranged and located, in conjunction with partitions and doors, as to compactly allow the provision of separate entrances to the

2

living room portions of both apartments and a common rear entrance from which access to the kitchen portions of both apartments or to the basement is afforded.

5 A further more specific object of the invention is to provide a duplex flat construction wherein the second floor apartment has a stair hall communicating with a single stairway and which stair hall is accessible to both the living room of the upper apartment and the kitchen thereof.

10 A further more specific object of the invention is to provide a duplex flat construction having a single stairway for the upper apartment communicating with a stair hall over a lower stair hall to which access from the exterior of the building is afforded by a rear door, said lower stair hall being separated from the stairway to the upper apartment by a partition with a controlling door therein.

20 A further object of the invention is to provide a duplex flat construction which in an economical and space-saving manner provides for privacy as between the upper and lower apartments while affording access to the desired front and rear portions of both apartments, which utilizes inexpensive structural arrangements to accomplish the desired end without sacrificing desirable space, and which is well adapted for the purposes described.

25 30 With the above and other objects in view, the invention consists of the improved duplex flat construction and its parts and combinations as set forth in the claims, and all equivalents thereof.

In the accompanying drawing in which the same reference characters indicate the same parts in both of the views:

35 Fig. 1 is a fragmentary first floor plan view of the improved duplex flat construction with the walls being shown in section; and

40 Fig. 2 is a similar fragmentary second floor plan view of that part of the duplex flat building which corresponds to and is located over the portion of the first floor flat shown in Fig. 1, with the walls being shown in section.

45 It should be understood that the present invention pertains to a duplex flat construction regardless of the specific room and architectural arrangements thereof, and pertains more particularly to the herein-described novel arrangements of doors, stairway, partitions and halls which permit of separate entrances to the living room quarters of both flats or apartments and a common rear entrance affording access to the rear stairway and the kitchen quarters of both apartments. The arrangement disclosed in the

drawing is merely typical and the invention is not limited thereto. In general, however, the upper and lower flats or apartments are symmetrically arranged.

The numerals 5 and 5' indicate the side enclosing walls of the building structure and the numeral 6 indicates the front wall thereof and all of the walls to effect the complete enclosure of the building are continued vertically upwardly above the second floor flat or apartment. Suitable windows 7 are arranged in desired portions of the various outside walls. The floor plan arrangement for a portion of the first floor flat or apartment is shown in Fig. 1. In one of the outside walls defining the lower apartment living room 8 is an entrance opening controlled by a door 9 whereby guests desiring access to the front portion of the lower floor apartment may enter directly thereto. The exact location of the lower floor front entrance door 9 is not critical. The living room 8 of the lower floor apartment, in addition to the exterior walls 5 and 6, is defined by interior walls or partitions 10 and 11. It will also be observed that the side wall 5' preferably terminates short of the front exterior wall 6 and the same, together with a short front side wall 12, provides an entrance alcove 13 for the upper apartment, as will hereinafter appear. Arranged parallel to the front wall 6 and extending from the interior wall 11 toward the exterior side wall 5' are spaced walls 14 and 15 defining a stairwell divided by an intermediate partition 16 parallel to the walls 14 and 15. An opening in that portion of the wall 14 which is adjacent the alcove 13 is controlled by a door 17 which leads from the exterior of the building into a small hall 18 from which extends, between the wall 14 and the partition 16, a stairway 19 leading to a landing 40 which is intermediate the floor levels of the lower floor apartment and the second floor apartment. Also controlling the lower stairway hall 18 is an opening therefor in the partition 16 is a door 20 separating a rear lower stair hall 21 from the lower front small hall 18. The side wall 5' in the lower apartment, in registry with the rear lower hallway 21, is provided with a rear doorway controlled by a rear door 22.

Rearwardly of the interior partition 15 and defined by other walls and partitions is the kitchen 23 of the lower apartment and the latter communicates with the lower stair hall 21 by means of a doorway in the partition 15 controlled by a door 24. Between the partitions 15 and 16 in the lower apartment and accessible from the lower stair hall 21 is a stairway 25 leading to the basement quarters for both apartments.

From the description thus far given it will be apparent that access to the front or living room portion of the lower apartment is gained through the front door 9. Access to the kitchen 23 of the lower apartment or to the basement is controlled by the rear door 22 which opens into the lower stair hall 21 from whence a person may directly descend the stairway 25 to the basement of the building or pass through the kitchen door 24 into the kitchen 23 of the lower apartment. Moreover, the small front hallway 18 is separated from the lower floor hall 21 by a door 20 which may be lock-controlled on either side for privacy, but, through control of the lock in said door 20, a person from the upper floor apartment, descending the stairway 19 into the front hall 18 may, by opening the controlled door 20, reach the stair hall 21 and from thence descend

to the basement via the basement stairway 25, or get to the exterior of the building through the rear entrance 22. The latter is the procedure for merchants and persons wishing to make deliveries to the kitchen of the upper apartment and the same class of persons may secure entrance through the rear door 22, stairhall 21, and door 24 to the kitchen 23 of the lower apartment.

If guests desire to reach the front or living room portion of the second floor apartment this is readily accomplished by entrance through the door 17 which is off the alcove 13 at the front of the building. With the door 20 closed and locked, such guests may not reach the rear lower stairhall 21 and are thus shut off from access to the basement or to the kitchen of the lower apartment and may merely utilize the stairway 19 leading to the second floor apartment.

Referring to Fig. 2 of the drawing, it will be evident that the exterior walls 5, 5' and 6, as well as the remainder of the walls to form the complete building enclosure, outline the second floor apartment which includes an upper living room 26 and an upper living room 26 and an upper kitchen 27. On the second floor level there are upwardly extending partitions 11', 14', 15' and 16' which correspond with the corresponding partitions of the lower floor apartment bearing the same unprimed numerals. The partitions 14', 15' and 16' define the stairwell which includes the stairway 19 leading from the hall 18 of the lower floor apartment upwardly to the previously mentioned landing 40 and from thence there is a stairway 23 leading to a second floor stair hall 29. From the latter, through a door opening in the partition 15' controlled by a door 30, access to the kitchen 27 to the upper apartment may be had. Also, for guests, from the second floor stair hall 23, the guests may pass through a doorway in the partition 14' controlled by a door 31 directly into the living room 26 of the upper apartment.

From the foregoing description it will be apparent that the improved duplex flat construction requires space for but a single stairwell in which are located the stairway to the basement and the stairway from the first floor small hall to the second floor stair hall and from the latter access may be had to either the front or living room quarters of the second floor apartment or the rear or kitchen portion thereof, with the result that via a front door 17, guests to the second floor apartment, utilizing the stairs 19 and 23, reach the second floor landing 29 and via the upper front door 31 may gain access to the living room quarters of the upper apartment. On the other hand, tradesmen, utilizing the same stairway and the rear door 22 and intermediate door 20, may reach the second floor stair hall and gain access to the upper kitchen 27 through the door 30. Via the same stairway anyone in the second floor apartment may reach the lower hall 18 and from thence through the door 20 to the basement stairway 25 or rear door 22.

As before mentioned, the lower floor apartment has the front door 9 for guests desiring to reach the front or living room portion of the apartment and the common rear door 22 gives access to the basement stairway 25 or to the kitchen door 24 of the lower apartment. The partitions and doors in the stairwell, particularly the intermediate partition 16 and controlled door 20, provide for complete privacy and separation as between the lower and upper apartments. The stair well is located laterally of the living rooms of both apart-

ments and between the kitchens and living room alcoves. Also, the stairs in the stair well communicate with first and second floor stair halls which are between the partitions defining the stair well, said stair halls communicating with the kitchens of the respective apartments.

By means of the improved duplex flat construction there is economy in space and construction costs, but a single stairwell is required although both apartments have separate front entrances, and a common rear entrance, and there is complete privacy and separation as between the accessible portions of the several apartments. The improved duplex flat construction is moreover simple and novel and is well adapted for the purposes set forth.

What is claimed as the invention is:

1. In a duplex flat building having a common rear entrance and separate front entrances for both the upper and lower flats, a lower hall into which the rear entrance and the front entrance for the upper flat both directly open, a stairway to the second floor flat accessible from a portion of said lower hall, a stairway descending directly from a portion of the lower hall to the building basement and disposed below a portion of the first-mentioned stairway, an upper hall to which the first-mentioned stairway extends, a stair well enclosing all of said stairways and contiguous with said halls, partitions on the second floor enclosing the stair well leading to the second floor, partitions on the first floor enclosing the stair well leading to the basement and to the second floor, said second floor partitions and said first floor partitions being vertically aligned, and doors controlling access from said upper hall to both the front and kitchen quarters of the upper flat.

2. In a duplex flat building including a basement and lower and upper flats, each of the latter having a front living room and a rearwardly disposed kitchen, a stairwell and hall area immediately interposed between the kitchens of both flats and portions of the living rooms of both flats, the building having a common service entrance in one of its walls and separate front entrances for both the upper and lower flats in other walls, a stairway to the second floor flat within said stairwell, an upper hall within the hall area to which said stairway extends and providing access to both the kitchen and living room of the upper flat, partitions in the upper flat enclosing the stair well area therein, partitions in the lower flat enclosing the stair well area therein, said upper flat partitions being vertically aligned with said lower flat partitions, contiguous front and rear lower halls within the hall area, the front lower hall providing direct access to said stairway and to the front entrance for the upper flat and the rear lower hall providing direct access to the service entrance and to the kitchen of the lower flat, a partition separating the front and rear lower halls, and a door in said partition.

3. In a duplex flat building including a basement and lower and upper flats, each of the latter having a front living room and a rearwardly disposed kitchen, a stairwell and hall areas immediately interposed between the kitchens of both flats and portions of the living rooms of both flats, the building having a common service entrance in one of its walls and separate front entrances for both the upper and lower flats in other walls, a stairway to the second floor flat within said stairwell, an upper hall within one of said hall areas to which said stairway extends and pro-

viding direct access to both the kitchen and living room of the upper flat, contiguous front and rear lower halls within another hall area, the front lower hall providing direct access to said stairway and to the front entrance for the upper flat, a basement stairway in said stairwell and underlying a portion of the first-mentioned stairway, the rear lower hall providing direct access to the service entrance, to the kitchen of the lower flat and to said basement stairway, a partition separating the front and rear lower halls, a door in said partition, partitions in the upper flat enclosing the stair well area therein, and partitions in the lower flat enclosing the stair well area therein, the last-mentioned partitions in the upper flat being vertically aligned with the corresponding partitions in the lower flat.

4. In a duplex apartment building including a basement and first and second floor apartments with the kitchen of the second floor apartment superimposed relative to the kitchen of the first floor apartment, a stairwell located forwardly of the apartment kitchens and adjacent a side wall of the building and housing a stairway to the building basement and a stairway from the first floor to the second floor, the stairwell also defining on the first floor level a pair of lower floor hallways and a second floor stairhall on the second floor level, the latter providing direct access to the second floor apartment kitchen and the stairway, and the lower floor hallways providing direct access to all of the stairways and to the lower floor apartment kitchen, a door controlling exterior entrance and egress to one of the lower floor hallways and basement stairway, a door providing exterior entrance and egress to the upwardly directed stairway, a front entrance door for the lower floor apartment, partitions in the upper flat enclosing the stair well area therein, and partitions in the lower flat enclosing the stair well area therein, the last-mentioned partitions in the upper flat being vertically aligned with the corresponding partitions in the lower flat.

5. In a duplex apartment building including a basement and first and second floor apartments, both of the latter having front living rooms and rearwardly disposed kitchens, portions of the respective kitchens and living rooms being separated, a stairwell located forwardly of the apartment kitchens and in the space which immediately separates said living rooms and kitchens and housing a stairway to the building basement and a stairway from the first floor to the second floor, there also being in said spaces a pair of adjoining lower floor hallways and a second floor stairhall, the latter providing direct access to the second floor apartment kitchen and to the second floor apartment living room and to the last-mentioned stairway, and the lower floor hallways providing direct access to all of the stairways and to the lower floor apartment kitchen, a door controlling exterior entrance and egress to one of the lower floor hallways, a door providing exterior entrance and egress to the other of said lower floor hallways and to the upwardly directed stairway, a front entrance door for the lower floor apartment, partitions in the upper flat enclosing the stair well area therein, and partitions in the lower flat enclosing the stair well area therein, the last-mentioned partitions in the upper flat being vertically aligned with the corresponding partitions in the lower flat.

6. In a duplex apartment building including a basement and first and second floor apart-

ments with the kitchen of the second floor apartment superimposed relative to the kitchen of the first floor apartment, a stairwell located forwardly of the apartment kitchens and adjacent a side wall of the building and housing a stairway to the building basement and a stairway from the first floor to the second floor, the stairwell also defining on the first floor level a pair of lower floor hallways and a second floor stairhall, the lower floor hallways being separated by a partition with a door therein, the second floor hallway providing direct access to the second floor apartment kitchen and to the stairway, and the lower floor hallways providing direct access to all of the stairways and to the lower floor apartment kitchen, a service door controlling exterior entrance and egress to one of the lower floor hallways, a front door providing entrance and

5 egress to the upwardly directed stairway, another front entrance door for the lower floor apartment, partitions in the upper flat enclosing the stair well area therein, and partitions in the lower flat enclosing the stair well area therein, the last-mentioned partitions in the upper flat being vertically aligned with the corresponding partitions in the lower flat.
